United States Patent Office

Des. 221,872
Patented Sept. 14, 1971

221,872

CABINET

Valentino Lancione, 908 Hazel Way,
Coraopolis, Pa. 15108

Filed Sept. 30, 1969, Ser. No. 19,354

Term of patent 14 years

Int. Cl. D6—04

U.S. Cl. D33—19

Fig. 1.

Fig.2.

FIG. 1 is a front perspective view of a cabinet showing my design; and

FIG. 2 is a front perspective view thereof with the doors in open position.

The rear walls and base of the cabinet are conventionally flat and unornamented.

I claim:

The ornamental design for a cabinet, substantially as shown and described.
